Robert S. Fairbanks
ATTORNEY.

UNITED STATES PATENT OFFICE

ANTHONY E. DAVIS, OF PHILADELPHIA, PENNSYLVANIA

LOCKING MECHANISM FOR RADIATORS

Application filed March 20, 1931. Serial No. 523,969.

The object of this invention is to devise a novel locking mechanism for radiators in order to prevent their accidental or unlawful removal after they have once been installed.

With the above and other objects in view, as will hereinafter more clearly appear, my invention comprehends novel locking mechanism for radiators to secure them with respect to their support.

It further comprehends a novel locking member adapted to cooperate with the tubes of a radiator and with the radiator supporting member to prevent improper removal of the radiator from its support.

It further comprehends a novel construction and arrangement of a support or carrier.

It further comprehends a novel construction of a locking member.

Other novel features of construction and advantage will hereinafter appear in the detailed description and the appended claims.

For the purpose of illustrating the invention, I have shown in the accompanying drawing preferred embodiments of it, which, in practice, will give satisfactory and reliable results. It is, however, to be understood that these embodiments are typical only and the various instrumentalities of which my invention consists can be variously arranged and organized, and the invention is not limited to the exact arrangement and organization of these instrumentalities as herein set forth.

Figure 1 is a side elevation of a radiator supporting bracket in assembled condition with respect to a radiator and having in conjunction therewith novel locking mechanism embodying my invention.

Figure 2 is a top plan view of the construction seen in Figure 1.

Figure 3 is a perspective view showing in detached position the radiator carrier or support.

Figure 4 is a top plan view of the locking member.

Figure 5 is a rear elevation of the locking member.

Figure 6 is a top plan view of another em-

bodiment of my invention showing a different construction of locking member.

Figure 7 is a front elevation of the locking member seen in Figure 6.

Figure 8 is a top plan view showing the locking member of Figures 6 and 7 in assembled relation with respect to a radiator.

Similar numerals of reference indicate corresponding parts.

Referring to the drawing:—

1 designates the body portion of a radiator bracket having openings 2 adapted to receive the bolts which secure the body portion 1 with respect to a wall. The lower end of the body portion 1 is deflected laterally as at 3 to form aligning means for the radiator 4, and the upper end of the body portion 1 is deflected in a similar manner, as at 5. An angle 6 is fixed to the body portion 1 by means of fastening devices 7 and is apertured to receive a bolt 8 which also passes through the upper deflected end 5 of the body portion 1. This bolt is in threaded engagement with a nut 9 and passes through the rearwardly deflected portion 10 of a radiator support or carrier 11. This support is cut out as at 12 in order to receive the nut 9 and prevent its revolution during the adjustment of the bolt 8. The radiator support 11 is in the form of a plate, the rearward portion of which is deflected to form a sleeve to receive the bolt 8 and its top is cut away or recessed as at 13 to receive the hub 14 of the radiator, the shape of this recess preferably conforming to the shape of such hub. The radiator support 11 is also provided with a slot 15 opening through its upper edge and preferably positioned near the rear end of the support 11.

The locking member 16 has its body portion in the form of a plate having a slot 17 opening through its bottom. This locking member 16 is deflected laterally at its upper end as at 18 to form a top member having the recess 19 so that it can be dropped downwardly between the side walls 20 of the juxtaposed tubes of the radiator. The top 18, at its rear end, is preferably cut away as indicated at 21.

The radiator is assembled with respect to its supporting bracket in the usual manner the radiator support 11 passing between jux-

taposed tubes so that the hub 14 of the radiator will be supported at the outer end of such plate. The locking member 16 is then dropped into position so that it assumes the position seen in Figures 1 and 2. It will now be apparent that this locking member 16 will prevent lateral removal of the radiator and if the radiator is raised upwardly or lowered the locking member will remain in locking position interlocking with the tubes and also with the radiator support 11.

In Figures 6 and 7 I have shown another embodiment of my invention in which the locking member 22 is provided with a downwardly extending slot 23 opening through its bottom and corresponding to the slot 17 of the locking member 16. The upper end of the locking member 22 is laterally deflected to form a top plate 24. This locking member is adapted to be employed in conjunction with radiator tubes 25 in which the side walls at the rear end of the tubes are of a different contour from that shown in Figure 2.

In accordance with my present invention I have devised a very simple and compact locking member which can be manufactured at a minimum cost and which will interlock with the radiator support and with the tubes of the radiator carried by such support.

The locking member is retained in position by gravity and after the radiator has been assembled with its support it is simply necessary to drop the locking member into position so that the wall above the slot 17 or 23 will be received in the slot 15 of the radiator support. The top of the locking member preferably rests on the top of the radiator support 11.

The radiator is locked in the aligned position in which it is supported and anchored on the radiator support.

It will now be apparent that I have devised a new and useful locking mechanism for radiators which embodies the features of advantage enumerated as desirable in the statement of the invention and the above description, and while I have, in the present instance, shown and described preferred embodiments thereof which will give in practice satisfactory and reliable results, it is to be understood that these embodiments are susceptible of modification in various particulars without departing from the spirit or scope of the invention or sacrificing any of its advantages.

Having thus described my invention what I claim as new and desire to secure by Letters Patent is:—

1. In a locking mechanism for radiators, a bracket having a body portion, a supporting member adjustably carried by said body portion and adapted to project between juxtaposed radiator tubes, said member having a seat and a slot opening through its top, and a locking member having a slot opening

through its bottom and provided with a top cooperating with the tubes to prevent removal of the radiator.

2. In a locking mechanism for radiators, an adjustably supported plate having a radiator supporting seat and a slot in its upper face, and a locking member in the form of an angle plate having a slot in its depending flange and having its top flange laterally deflected.

3. A radiator support adapted to pass between tubes of a radiator, and provided with a seat, a radiator adapted to engage said seat, and a locking member adapted to move down between juxtaposed tubes into locking engagement with said support, and to lock with the walls of juxtaposed tubes to prevent removal of the radiator.

ANTHONY E. DAVIS.
